UNITED STATES PATENT OFFICE

EDWARD S. PLIMPTON, OF DENISON, IOWA.

CAR-COUPING.

SPECIFICATION forming part of Letters Patent No. 230,493, dated July 27, 1880.

Application filed May 20, 1880. (No model.)

To all whom it may concern:

Be it known that I, EDWARD S. PLIMPTON, of Denison, in the county of Crawford and State of Iowa, have invented a new and useful Improvement in Car-Couplings, of which 5 the following is a specification.

My invention is an improvement in the class 10 of car-couplings in which the coupling-pin is provided with an arm that projects from the head thereof and rests in a socket in the front top portion of the draw-head, so as to constitute a fulcrum on which the pin may swing when pushed back by the link in the operation of coupling.

15 My improvement consists in constructing the coupling-pin with lateral studs or projections at its lower end, and in providing the top portion of the draw-head with a slot and notches, so as to allow the pin to be raised 20 and supported in inclined position above the cavity of the draw-head, as hereinafter described, and shown in the accompanying drawings.

25 In the accompanying drawings, Figure 1 is a top view of a coupling embodying my improvements. Fig. 2 is a longitudinal vertical section. Fig. 3 is a front view, partly in section.

Similar letters of reference indicate 30 corresponding parts.

The draw-head A may be of any suitable general construction which will admit of the application of my improvements. As here shown, it is constructed with a view to the 35 employment of three links and pins, the links being the same as those in common use. The two outer links are to be coupled laterally and the central one longitudinally.

40 The coupling-pin B is curved forward and then downward at its upper end, which is provided with trunnions b b, forming the pivots on which it swings. This curved portion of the pin rests in a recess in the draw-head formed by two projecting ribs or inclined 45 planes, D D, which serve as guards to protect the pin from injury by the link of an approaching car in case said link may be raised too high. The pin B works in slots s in the draw-head, the front ends of which slots are in a 50 vertical line with each other.

It will be seen on reference to Fig. 2 that by pivoting the pin at a point considerably forward of the front ends of these slots the pin is allowed sufficient play for the passage of the link without the necessity for its rising 55 very high. As the end of the link of the approaching car enters the mouth of the draw-head it strikes the pin B and causes it to swing backward until its lower end is passed, whereupon the pin again drops to the position shown in Fig. 2.

When the cars are to be uncoupled the pin B is raised vertically until two lateral studs, e e, near its lower end, have passed through notches g g in the upper slot, s, and are clear 65 of the slot. The pin is then leaned backward to the position shown in dotted lines, in which position it is held by two lateral studs, f f, lower down than the others, engaging with the inner surface of the draw-head on either 70 side of the slot.

For holding the link in position to enter the mouth of the draw-head of an approaching car, I employ a triangular block, H, pivoted at its highest angle in a recess in the 75 draw-head and having a flat spring, J, engaging with its base, so as to hold it with one of its angles protruding beyond the edge of the recess and extending slightly into the mouth of the recess. By placing the inner end of 80 the link L under this protruding angle, as shown in Fig. 2, the link is held in such a position as to insure its entrance into the approaching draw-head. The spring J allows the block H to yield if struck by the link on 85 its forward side.

The pins for coupling the two outer links may be like the one above described, and arranged to swing transversely, as shown in Fig. 3, or they may be round pins of the usual 90 form, as shown by the letter M.

The pin B may be provided with two branches at its upper end, in which case it may be reversed when necessary. By hanging the pin at a point forward of its longitudinal center 95 it has a greater rise rearward, and its weight returns it to and holds it in its vertical position.

The pin may be raised by a cord or rod operated from the top of the car, and all three 100

of the pins may be raised at once by having them suitably connected.

Having thus described my invention, I claim as new and desire to secure by Letters Patent—

The combination, with the draw-head A, having its top slotted and provided with notches *g*, as shown, of the coupling-pin B, provided

with the lateral studs *e* and *f* at its lower end, whereby it is adapted to be supported, as described.

EDWARD SEAGRAVE PLIMPTON.
